CLAIM

The ornamental design for a chip-collecting attachment for a hand-held air drill, as shown and described.

DESCRIPTION

FIG. 1 is a top, front and right side perspective view of a chip-collecting attachment for a hand-held air drill showing my new design;

FIG. 2 is a sectional view thereof taken on line 2—2 of FIG. 1;

FIG. 3 is a front elevational view thereof;

FIG. 4 is a rear elevational view thereof;

FIG. 5 is a top plan view thereof;

FIG. 6 is a right side elevational view thereof;

FIG. 7 is a left side elevational view thereof; and

FIG. 8 is a bottom plan view thereof.

FIG. 3

FIG. 4

FIG. 2

FIG. 1
